Attorney.

UNITED STATES PATENT OFFICE.

LEE S. BURRIDGE, DECEASED, LATE OF NEW YORK, N. Y., BY FRANCIS O. BURRIDGE, EXECUTOR, OF NEW YORK, N. Y., ASSIGNOR, BY MESNE ASSIGNMENTS, TO UNDERWOOD TYPEWRITER COMPANY, OF NEW YORK, N. Y., A CORPORATION OF DELAWARE.

DESIGN FOR A TYPE-WRITING MACHINE.

52,907.

Specification for Design.

Patented Jan. 28, 1919.

Application filed July 27, 1918. Serial No. 247,074. Term of patent 14 years.

To all whom it may concern:

Be it known that LEE S. BURRIDGE, deceased, late a citizen of the United States, and late residing in the borough of Manhattan, county, city, and State of New York, invented a new, original, and ornamental Design for Type-Writing Machines, of which the following is a specification, reference being had to the accompanying drawing, forming part thereof.

The figure is a perspective view of a type-writing machine, showing the new design.

Copies of this patent may be obtained for five cents each, by addressing the "Commissioner of Patents, Washington, D. C."

Claim:

The ornamental design for a typewriting machine, as shown.

FRANCIS O. BURRIDGE,
Executor of the last will and testament of Lee S. Burridge, deceased.

Witnesses:

NELLIE M. BROWN,
CHARLES W. HOWELL.
